Marion Block
ATTORNEY

UNITED STATES PATENT OFFICE.

WILLIAM F. MULLER, OF BROOKLYN, NEW YORK.

REFILLABLE ELECTRIC FUSE.

1,317,381.

Specification of Letters Patent. Patented Sept. 30, 1919.

Application filed December 18, 1918. Serial No. 267,235.

To all whom it may concern:

Be it known that I, WILLIAM F. MULLER, a citizen of the United States of America, residing at Brooklyn, Kings county, State of New York, have invented certain new and useful Improvements in Refillable Electric Fuses, of which the following is a full, clear, and exact description.

This invention relates to improvements in fuses, the chief object being to provide an inexpensive refillable fuse or a fuse that can be rendered again usable after it has been blown out. I employ the term fuse to indicate a suitable casing or container having a fusible element within same, such term being generally employed in the electrical trade. My invention has for an object to provide such a container or casing arranged for the insertion of a fusible element after the fuse 20 has blown, thereby rendering the casing usable as many times as desirable.

I will now proceed to describe in what manner I carry out my invention, reference being had to the accompanying drawing, for 25 an illustration of an embodiment of my invention, wherein:

Figure 1 illustrates a sectional view of my invention embodied in the form of a plug-fuse;

Fig. 2 is a top plan view thereof on a reduced scale;

Fig. 3 is a fragmentary sectional view of a modified form of my invention; and

Fig. 4 is a longitudinal sectional view of a 35 cartridge fuse embodying my improvement.

To embody my improvement in the form of a plug-fuse, I employ a chambered casing or container 5 carrying a threaded sleeve 6 of conducting material, to engage the 40 threads of a socket, the casing being formed out of non-conducting material. In this instance one end of the casing is enlarged as at 7 and provided with threads 8, on the periphery thereof, to engage the threads of a 45 removable cap 9. One end of the casing carries a screw contact 10 around which one end of a fuse-wire 11 is wound. The other end of the fuse-wire is wound around a threaded binding-post 12 carried by a removable plate 13 of conducting material, which is maintained in contact with pins 14 (in this instance) which extend through the casing 5 and engage the shell 6; hence the 50 circuit in which the fuse is placed will include contact 10, fuse 11, plate 12, pins 14

and shell 6. The plate 13 is maintained in contact with the pins 14 by a spring 15 bearing at one end thereof against the cap 9 which, in this form of my invention, is made out of non-conducting material. Instead of employing a cap such as 9, and a spring, I may provide a metal cap, such as is indicated by 16, Fig. 3, carrying a post 17 provided with a tip 18 of insulating material (rubber for instance), the resiliency of which will maintain plate 13 in contact with pins 14. As will be seen, the tip 18 will be recessed as at 19 to receive the head of the binding-post 12. Should the fuse 11 blow out, it will simply be necessary to remove cap 9, take out the plate 13, and remove the fragments of the blown fuse, and insert a new fuse (such a fuse being a part of a coil of fusible wire in which form this type of fuse is usually provided). One end 70 will be passed through opening 20 in one end of the casing 5. The wire will now be drawn through chambers 21 and 22 and the end thereof passed through opening 23 in the now removed plate 13, after which it 75 will be wound around the now loosened binding-post 12, which will be screwed down after the wire has been wound therearound. After having performed the above mentioned operation, the plate 13 can be drawn 80 into chamber 22, and against pins 14, by pulling the wire from the end or nose 24 of the plug. After the plate has been thus drawn into place, the wire will be wound around contact 10 and cut off, whereupon 85 the contact may be screwed down. After spring 15 has been placed in position within chamber 22, cap 9 can be placed in position and screwed home. The spring 15 will now maintain plate 13 in contact with pins 14. 90

To embody my invention in the form of a cartridge-fuse, I employ an elongated chamber or tube 25 of non-conducting material (see Fig. 4), having sleeves 26 and 27 at opposite ends thereof. One end of the tube 25 carries a fixed plate 28 of conducting material, which is electrically connected to its adjacent sleeve 27. The opposite end of the tube 25 carries a removable plate 29 of conducting material, held in contact with pins 105 30 connected to sleeve 26 by a plug 31 of insulating material threaded into the end of the tube 25. The fuse 32 is secured to fixed plate 28 by a binding-screw 33, and to the plate 29 by a binding-screw 34. Each plate 110

28 and 29 is provided with an opening 35 for the passage therethrough of the fuse 32. The openings for the passage of the fuse in both forms of my invention, will be approximately the size of the wire; hence the danger of inserting a fuse, that is too large, will be prevented. A fuse that is too small will not endanger the line protected by the fuse. As the size of the wire and length, 10 thereof will be proportioned to the amperage to be carried, there will be no danger of refilling a fuse with any but the proper length; that is to say, a wire that is too large cannot be passed through the openings provided for the passage of a wire of a diameter suitable for a predetermined amperage.

Having described my invention, what I claim is:—

30 1. A fuse consisting of a chambered casting, having an open end, a conducting element on the exterior surface thereof, a contact at one end of the casing, out of electrical contact with said conducting element, 25 and arranged for the attachment of a fusible element thereto, a removable support within the casing of conducting material, means carried thereby to engage the opposite end of the fusible element engaged by said contact, means to electrically connect the support within said casing with said exterior conductor, and a non-conducting cap to close the open end of the casing arranged to maintain the removable support 35 within the casing in position.

2. A fuse consisting of a chambered casting of non-conducting material, open at one end thereof, a contact at the closed end of the casing adapted for the attachment thereof to a fusible element, a removable conducting element within the casing adjacent the open end thereof, a conducting shell carried by the casing exteriorly thereof, pins passing through the wall of said shell to electrically connect said shell with said interior

conducting element, and yieldable means to retain said interior conductor in position.

3. A fuse consisting of a chambered casting, open at one end thereof and provided with an opening in the closed end thereof 50 for the passage of a fuse wire, a contact adjacent said opening for the attachment thereto of one end of the fuse wire, a loosely mounted removable plate within the chamber, means to secure the other end of 55 said fuse wire to said plate, and a non-conducting element at the open end of said chamber to retain said plate in position.

4. A fuse consisting of a chambered casting, open at one end thereof and provided 60 with an opening in the closed end thereof for the passage of a fuse wire, a contact adjacent said opening for the attachment thereto of one end of the fuse wire, a removable plate within the chamber, means 65 to secure the other end of said fuse wire to said plate, a cap of non-conducting material for the open end of said casing, and a spring interposed between said plate and said cap.

5. A fuse consisting of a chambered casting, open at one end thereof and provided with an opening in the closed end thereof for the passage of a fuse wire, a contact adjacent said opening for the attachment 75 thereto of one end of the fuse wire, a removable plate within the chamber, means to secure the other end of said fuse wire to said plate, a cap of non-conducting material, having a threaded engagement with 80 said casing at the open end thereof, and a spring interposed between the cap and said plate.

Signed at New York city, N. Y., this 16 day of December, 1918.

WILLIAM F. MULLER.
